CLAIM

The ornamental design for a combined swaddle and sleep bag, as shown and described.

DESCRIPTION

FIG. 1 is a perspective view of a combined swaddle and sleep bag showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the combined swaddle and sleep bag where the combined swaddle and sleep bag is in a first configuration of use; and,

FIG. 10 is a perspective view of the combined swaddle and sleep bag where the combined swaddle and sleep bag is in a second configuration of use.

The broken line outline of the partial human figure in FIGS. 9-10 assists in illustrating how the combined swaddle and
